POWERED WIRE DRILL

Carl L. Foltz, Holiday, Fla., assignor to Concept, Inc.,
St. Petersburg, Fla.

Filed Apr. 17, 1972, Ser. No. 245,026

Term of patent 14 years

Int. Cl. D8—01

U.S. Cl. D8—68

FIG. 1 is a top plan view of the powered wire drill showing the protector cap removed from the forward end thereof.

FIG. 2 is a side view of the powered wire drill.

FIG. 3 is a bottom view thereof.

FIG. 4 is a front end view thereof.

FIG. 5 is a rear end view thereof.

I claim:

The ornamental design for the powered wire drill, as shown, and described.
